UNITED STATES PATENT OFFICE.

JOHANNES JACOBSEN, OF FRIEDENAU, NEAR BERLIN, GERMANY.

HYDRAULIC PRESS FOR CONTINUOUSLY-FED PASTY OR LOOSE MATERIAL.

1,073,856.

Specification of Letters Patent. Patented Sept. 23, 1913.

Application filed March 23, 1909. Serial No. 485,335.

To all whom it may concern:

Be it known that I, JOHANNES JACOBSEN, engineer, a subject of the German Emperor, residing at 33/34 Cranachstrasse, 5 Friedenau, near Berlin, Germany, have invented certain new and useful Improvements in Hydraulic Presses for Continuously-Fed Pasty or Loose Material; and I do hereby declare the following to be a full, 10 clear, and exact description of the invention, such as will enable others skilled in the art to which it appertains to make and use the same.

The invention relates to a hydraulic press 15 for continuously fed pasty or loose material, in which the material is fed into a feed box and moved into the working position independently of the pressram, said box being removed after the pressing stroke has been 20 given, so as to leave the finished piece free to be ejected.

According to the present invention, the above mentioned box is connected to a subsidiary pressram in such a manner that it 25 is moved into working position before the main ram begins its stroke and returns to its initial position before the main ram begins its back stroke.

The invention further relates to an appliance for reversing the action of the press. 30 Appliances for automatically reversing the action of a hydraulic press by diverting the liquid to the rear of the ram, are known. In the known presses the reversing slide 35 valve is however held in position by friction only, and is opened by the liquid as soon as the pressure rises above a certain point. It will be easily understood that such a device can not possibly work with exactitude, 40 in the first place because of the difficulty of exactly establishing the necessary amount of friction, and secondly because the friction is gradually diminished by the working of the machine.

According to the present invention, the 45 force necessary to automatically reverse the action of the press, is determined with great exactitude by providing stops to secure the slide valve in its extreme positions, said 50 stops being released by members actuated by a determined force (weights or springs) which is overcome by the rising pressure of

the liquid. The valve slide is then carried over to its other extreme position, and thereby opened.

In the accompanying drawings several 55 embodiments of my invention are illustrated.

Figure 1 is a longitudinal section through a press according to the invention, showing the connecting conduits diagrammatically. 60 Fig. 2 is a detail in cross section, showing the box in which the material is deposited and pressed. Fig. 3 is a detail section on line 3—3 of Fig. 2. Fig. 4 is a side elevation of a reversing device, partly in section, 65 and showing the slide valve stopped by joint levers, which are doubled up by weighted members adapted to be lifted by the rising pressure. Fig. 5 is a horizontal section through the same embodiment of my invention 70 showing the reversing mechanism. Fig. 6 is a detail showing the weighted member by which the stop is released. Fig. 7 is a side view of another embodiment of my invention in which the slide valve is stopped 75 by wedges.

In a hydraulic cylinder 1, a piston 2 is adapted to slide, which carries on each end a ram 3. Opposite the ram 3 subsidiary rams 4 fitted on small pistons 5 are provided to 80 throw out the finished pieces. The pistons 5 also move in separate hydraulic cylinders. The cylinder 1 is connected to the apparatus supplying the liquid to the press by the sockets 6 and 7. The connection is reversible, so that the socket 7 may communicate with the drain pipe, while the socket 6 is connected to the pressure pipe and vice versa. Each ram is surrounded by a box 8 funnel shaped at the top and connected at the bottom to a small piston 9, both ends of which move in small hydraulic cylinders 10. One of these cylinders is always in connection with the pressure pipe and the other with the drain pipe. It is preferable to have 90 the machine as a whole offset from the vertical, as indicated in Fig. 2, the structure presenting a considerable angle to a vertical plane.

In the position of the press rams and boxes 100 shown in Fig. 1, the socket 7 is assumed to be in communication with the delivery pipe, and the socket 6 with the drain pipe. On the right hand side of the figure the parts are

shown in the position they occupy just before the pressing stroke is finished, whereas on the left hand side the stroke has not yet begun. The left hand cylinder 10 is connected to the right hand cylinder 1 by a conduit shown diagrammatically by the dot and dash lines in the drawing, the lefthand cylinder containing the piston 5 with the righthand cylinder 1 and in the same way 5 the right hand cylinder 10 with the lefthand cylinder 1, and the righthand cylinder containing the piston 5 with the lefthand cylinder 1. When therefore the connection of the sockets 6 and 7 with the pressure pump 10 is reversed, which may be done in any known manner, the action of the parts will be as follows: The left hand cylinder 10 is connected to the drain pipe and the right hand cylinder 10 with the delivery pipe. 15 The left hand box is thereby carried to the left into the gap between the ram 3 and the ejector 4, and leaves the column of material 11, which till then rested on a plate 12 at the upper end of the box 8, free to be fed 20 into the box. At the same time the box 8 releases an arm 13, which engages the box 8 by means of an adjustable screw 14. The arm 13 follows the moving box under the influence of a spring 15, till a flap 17 connected with the arm and hinged onto the lower end of the conduit feeding the material engages the material to prevent it from being fed downward into the box. 25 This condition of things is shown on the righthand side of Fig. 1. In the meantime a wire 19 (Fig. 2) stretched out between two arms 18 attached to the box 8, has cut off the bottom part of the column of material 11, so that it falls down into the box 8. 30 The piston 2 is now carried over to the left, and the lefthand ram 3 pressed against the material in the box, which is held between the ram 3 and the ejector 4. The ejector 4 slowly recedes before the main ram, though 35 exercising a counter pressure. The ram 3 and the ejector 4 enter the chamber of the press 20, as shown in Fig. 1. The counter pressure of the hydraulic ejector may be regulated by a valve or other regulating device, provided in the drain pipe belonging to it. 40 When the fluid is admitted to the cylinders 1 and 10 the piston in the latter cylinder will be forced to the other end of its 45 stroke before the piston 2 has been moved through the entire length of its cylinder. This is due to the fact that the resistance offered by the feed box which is secured directly to the piston 9 is smaller than that offered by the pistons 2. When the fluid is admitted to both cylinders simultaneously, the feed box will be moved to its other extreme position rapidly and without offering much resistance whereas the piston 2 50 will travel more slowly due to the resistance

by its immediate parts. The same is true when both of said cylinders are connected to the drain pipe and the piston 9 will return the feed box to its original position faster than the piston 2 will return to its 55 original position. In short as the piston 9 is more sensitive to the motive fluid due to the small resistance offered by its immediate parts, it will always operate slightly in advance of the heavier and larger proportioned parts actuated by the pistons 2. 60

When the press is again reversed, the series of movements just described is repeated on the right hand side of the press. On the righthand side, the finished piece has been ejected during the forward or pressing stroke on the left. At the same time that the lefthand box is moved under the column of material, the right hand box moves from under it, meets the movable arm 13 and by 65 compressing the spring 15, releases the column of material held by the flap 17. The column falls downward onto the plate 12, as is shown in Fig. 1 on the lefthand side. At the same time the right hand box 8 has 70 released a hinged chute 22 controlled by a spring 21. In its position under the column of material the box moves this chute aside, by engaging a projection 23. When therefore the right hand ram 3, follows the reversed main ram 2 to the left, the ejector 4 follows also, and ejects the finished piece into the gap left by the righthand box 8. During this movement the finished piece receives a slight push from the chute 22, 75 which is thrown forward by its spring 21, so that the piece is disengaged from the ejector 4 and slides down from the chute. 80

In case loose material is to be treated in the press, the appliance (18, 19,) for cutting 85 through the column of material may of course be omitted, and other means must be employed in place of the flap 17 to feed a determined quantity of material into the boxes 8, for instance a slide. 90

In the embodiment of the reversing gear according to my invention illustrated in Figs. 4 to 6, the valve slide *a* is provided on each side of the socket *b* with collars *c*, *c'* of large diameter, and collars *d*, *d'* of 95 smaller diameter. These collars fit tightly in the borings *e*, *e'* and *f*, *f'* in the chamber of the reversing gear. Between the borings *e*, *e'* on the one hand, and *f*, *f'* on the other hand, the wall of the valve chamber is fitted 100 with grooves *g*, *g'*, which make connection with the sockets *h*, *h'* leading to the hydraulic press. 105

Both ends of the slide valve *a* are attached to the outer ends of toggle levers *i*, *i'*, the 110 inner ends of which are pivoted to the valve chamber at *k*, *k'*. The joints *l*, *l'* of the toggle levers are pivoted on journals *m*, *m'* carried on loops *n*, *n'*, surrounding the ends of the valve chamber, (Fig. 6). The loops *n*, 115

n' are attached to levers *o*, *o'*, pivoted on the valve chamber in any suitable manner. Both levers engage small pistons *p*, *p'* adapted to slide in cylinders *q*, *q'*. The cylinders *q*, *q'* communicate with the grooves *g*, *g'* in the wall of the valve chamber.

The action of the parts described is as follows: In Figs. 4 and 5 the feeding conduit *b* communicates with the socket *h'*, which makes connection with one side of the piston of the hydraulic press. The opposite side of the piston communicates by means of the socket *h* and the borings *g* and *f* with the drain pipe. The collar *d'* of the slide valve is positioned in the boring *f'*, and thereby separates the feeding conduit from the right hand drain of the valve chamber. The collar *c* registers with the boring *e*. The right hand toggle lever *i'* is stretched out and is kept in this position by the weights *r'* attached to the loop *n'*. The toggle lever *i* is therefore naturally in its doubled up position. The pressure of the liquid fed into the reversing gear acts on the slide valve in two opposite directions, that is leftward on the collar *c* and rightward on the collar *d'*. As the area of the collar *c* is larger than that of *d'* the pressure tends to displace the slide valve from the position shown into its other extreme position. The valve is however prevented from executing this movement by the toggle lever *i*, *i'*, which is stretched out to its full length. When the pressure rises in the hydraulic press, it also rises in the parts of the slide valve chamber which are in communication with the press. Accordingly the pressure acts on the small cylinder *q'* and lifts the lever loop *n'* together with the weights attached to it when the pressure has attained a certain height. The loop *n'* moves upward and doubles up the lever *i'* by means of its journals *l'*. The slide valve can now follow the pressure acting on the larger area of the collar *c*, and accordingly moves into its opposite extreme position. The toggle lever *i* is thereby straightened and the lever *o* engages the piston *p*. The movement of the slide valve has opened the communication between the feed conduit *b* and the socket *h*, and the socket *h'* communicates with the righthand drain of the valve chamber. The pressure in the small cylinder *q'* is thereby relieved and the piston *p'* is lowered. The lever *o'* however remains in its raised position together with a loop *n'*, because the straightened knee lever *i* prevents the slide valve from moving to the right,

and the knee lever *i'* from straightening under the influence of the weights.

The loops *n* and *n'* are provided with cushions *s* and *s'*, to break the impact of their fall onto the slide valve chamber. 65

In the embodiment of my invention illustrated in Fig. 7 the slide valve is stopped by wedges *t*, and *t'*, moving in wedge shaped grooves *u*, *u'* of the valve chamber. The interior parts of the reversing gear are the 70 same as those shown in Fig. 5.

The pressure of the hydraulic press which is to actuate the automatic reversing gear may be controlled by varying the weights *r*, *r'*. In place of the weights springs may 75 also be employed, the tension of which is controlled in a known manner.

Claims—

1. Hydraulic press for continuously fed 80 pasty or loose material, fitted with a box into which the material to be pressed is fed, characterized in that the main ram passes transversely through an opening in the movable feed box and performs the working stroke against a gradually receding subsidiary ram, which during the back stroke of the main ram advances in its turn and ejects the finished piece. 85

2. Hydraulic press for continuously fed 90 pasty or loose material, characterized by a movable feed box actuated by a subsidiary hydraulic piston, a spring controlled chute carrying a projection adapted to be pressed aside by the said box, as it is moved into working position, and released as it goes 95 back to its initial position, so that the finished piece receives a slight blow from a projection on the chute and is disengaged from the ejector ram.

3. A hydraulic press for continuously fed 100 pasty or loose material provided with a feed box into which the material to be pressed is fed, a subsidiary hydraulic piston to actuate said feed box, a main ram adapted to pass transversely through an opening in the movable feed box, a subsidiary ram which gradually recedes during the working stroke of the main ram and advances in its turn during the back stroke of the main ram to eject the finished piece of material, and a reversing 105 valve to control the supply of fluid to said subsidiary piston and to said main and subsidiary rams. 110

In testimony whereof I have affixed my signature, in presence of two witnesses.

JOHANNES JACOBSEN.
